LOUIS P. DISS, OF ILION, NEW YORK. **BEST AVAILABLE COPY.**

TYPE-WRITER RIBBON-FEED.

No. 904,816.

Specification of Letters Patent.

Patented Nov. 17, 1908.

Application filed November 14, 1897. Serial No. 402,063.

To all whom it may concern:

Be it known that I, LOUIS P. DISS, of Ilion, in the county of Herkimer and State of New York, have invented certain new and useful Improvements in Type-Writer Ribbon-Feeds; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my present invention is to provide an improved ribbon feeding mechanism for typewriting machines, which is simple and efficient in operation and arranged to automatically reverse the feed of the ribbon.

Figure 1 shows a partial sectional view of the frame of the typewriter machine with my improved mechanism in position therein. Fig. 2 is a plan view of a part of a typewriter machine with my improved mechanism introduced therein. Fig. 3 is a cross sectional view through one of the spools constituting a portion of the mechanism, this section being taken at right angles to the section shown in Fig. 1. Fig. 4 is an enlarged detail showing features of the device, in connection with a section of a portion of the frame. Figs. 5 and 6 show on an enlarged scale details in two positions which the parts are capable of assuming. Fig. 7 is a cross section through the spool.

In the drawings there is shown only so much of a typewriting machine as is necessary to illustrate the invention.

Referring to the drawings *a* indicates what is usually termed the top plate, being the upper portion of the frame of the machine. In opposite corners of the top of the machine or top plate *a* there are provided depressed cups *b*—*b* adapted to receive and incase a portion of the mechanism. Immediately over these cups *b* are located the ribbon spools *c*—*c*, the same being mounted on a sleeve *d* revolving on a fixed spindle *e* centrally arranged in the cup *b* and projecting vertically. On the lower end of the sleeve *d* there is provided a gear pinion *f* secured to the sleeve and thus to the spool so as to rotate the same on the spindle *e* when power is applied. In the plane of the pinion *f* there is provided the driving pinion *g* adapted to mesh therewith and mounted on the swinging upper

end of the shaft *h*. The shaft *h* at its lower end is provided with a gear pinion *i* meshing with a gear pinion *j* on the horizontal shaft *k*. The shaft *k* is mounted in suitable fixed 60 bearings in the frame and provides bearings for the oscillating hanger *l* having bearings in which the shaft *h* is mounted. There is a shaft *h* on each side of the machine, and these shafts are provided at their rear ends 65 with beveled gear pinions *m* meshing with beveled gear pinions *n* provided on the back shaft *o*. Power for driving the ribbon spools is applied to the shaft *o* and causes the shafts *h* and *h* on the one side of the machine to 70 rotate in unison with the similar shaft on the other side of the machine but in the opposite direction. The upper swinging ends of the hangers *l* on the opposite sides of the machine are connected by a rod *p* which 75 spaces these hangers at such a distance that only one at a time of the gear pinions *g* can engage the pinion *f* connected with the spool. This rod *p* is provided with a projection *q* having preferably three teeth engaged by a 80 spring click *r* mounted on the frame.

Attached to the underside of the spool by the depending arms *s*, which are preferably connected at their upper ends by a semi-circular bar *t*, is the semi-circular cam carrier *u*, 85 This cam carrier *u* at its opposite extremities is hinged to the lower ends of the arms *s* as indicated by *s'*. The cam carrier *u* is provided with a cam or wedging piece *v* adapted to engage with the gear pinion *g* 90 and preferably provided on its operative face with three or four teeth of a size and shape to adapt them to mesh with the teeth of the gear pinion *g*. For controlling the position of the cam carrier *u* it is provided 95 with an arm *w* which projects upwardly through a slotted opening *c'* in the lower flange of the spool *c* and is at its upper end adapted to occupy a position lying against the core of the spool or swing to the outer 100 end of the slot *c'*, where the movement is limited at the position with the arm and cam carrier in the plane of the gear pinion *g*. The arms *s* are springs resting under tension 105 against stops *x*. This allows the cam carrier to shift sufficiently under excessive pressure to permit the teeth of the cam and gears to find their meshing position without blocking the operation. The teeth of both the cam and the gears will be preferably made 110 quite sharp at the point in order to facilitate their entering.

The ribbon, of course, is attached at each end to the core of the spools *c* and between the spools passes in close position to the platen indicated by *A* where the type may engage the same in well known manner. In operation one spool is released while power is applied to the other to rotate the same and wind the ribbon thereon. It is obvious that while ribbon is wound around the core of a spool, that it will bind the upper swinging end of the arm *w* to the core and throw up the cam carrier *u* with its cam into the inclined position shown in Fig. 4 where the cam will not engage with the gear pinion *g* as the spool revolves. When, however, the ribbon has been unwound from a spool sufficiently to release the arm *w*, the cam carrier drops into its horizontal position, as shown in dotted lines in Fig. 4. Then as the spool *c* revolves under the influence of the ribbon being unwound therefrom, the cam *v* is brought around into position to engage with the gear *g*. As the gear *g* is always driven, it furnishes its own power to force the cam *v* past itself and in so doing the gear *g* is forced over by the cam towards the gear *f*. In this operation the spring click *r* rides out of one of the depressions in which the point engages and sufficiently over the high point so that the action of the spring click completes the movement and throws the gear *g* out of engagement with the cam *v* and into engagement with the gear *f*. By reason of the connecting rod *p* when the gear pinion *g* of one side of the machine is being thrown into engagement with the gear pinion *f* on that side, the one on the opposite side is thrown out making the spool on the opposite side of the machine then the free spool. The first partial revolution of the empty spool causes the ribbon to bind the swinging end of the arm *w* against the core and elevates the cam carrier into its inoperative position. It is obvious that the spool driving mechanism may be shifted manually at any time, and for this purpose a knob or handle *z* is provided.

While the teeth on the cam *v* are preferable, it is obvious that the teeth may be omitted and that other modifications and changes in the construction can be made without departing from the spirit of my invention.

What I claim as new and desire to secure by Letters Patent is:

1. The combination in a typewriter of a ribbon spool having a driving pinion attached, primary and secondary driving shafts arranged at angles and connected for rotation, a swinging hanger mounted on bearings concentric with the primary shaft and carrying the secondary shaft in bearings therein, a pinion on the swinging end of the secondary shaft arranged to engage the pinion on the spool and means for shifting

the position of said pinion, substantially as set forth.

2. The combination in a typewriter of a pair of ribbon spools each having pinions attached, primary and secondary driving shafts for each spool arranged at angles and connected for rotation, a swinging hanger mounted on bearings concentric with the primary shaft and carrying the secondary shaft in bearings therein, pinions on the swinging ends of said secondary shafts respectively arranged to engage the pinions of the spools respectively, a connection between the said hangers and means for shifting the position of said hangers to engage and disengage the pinions carried thereby with the spool pinions, substantially as set forth,

3. The combination in a typewriter machine of a ribbon spool having a gear pinion attached, a movable driving pinion adapted to engage and disengage said spool pinion, a movable cam carrier mounted on the spool and adapted to swing around the said driving pinion, a cam mounted on the carrier and adapted to engage and move the driving gear pinion, and a controlling arm on the cam carrier projecting into the ribbon space of the spool, substantially as set forth.

4. The combination in a typewriter machine of a ribbon spool having a gear pinion attached, a movable driving pinion adapted to engage and disengage said spool pinion, a movable cam carrier mounted on the spool by spring arms and adapted to swing around the said driving pinion, a cam mounted on the carrier and adapted to engage and move the driving gear pinion, and a controlling arm on the cam carrier projecting into the ribbon space of the spool, substantially as set forth.

5. The combination in a typewriter machine of a ribbon spool having a gear pinion attached, a movable driving pinion adapted to engage and disengage said spool pinion, a movable cam carrier mounted on the spool by means of spring arms and stops to limit the movement of said spring arms, the cam carrier arranged to swing around the said driving pinion, a cam mounted on the carrier and adapted to engage and move the driving gear pinion, and a controlling arm on the cam carrier projecting into the ribbon space of the spool, substantially as set forth.

6. The combination in a typewriter machine of a ribbon spool having a gear pinion attached, a movable driving pinion adapted to engage and disengage said spool pinion, a substantially semi-circular cam carrier, stops mounted on the spool, spring arms held under tension against the stops to the free ends of which the cam carrier is hinged and arranged to swing around the said driving pinion, and a cam mounted on the carrier and adapted to engage and move the driving

gear pinion, and a controlling arm on the cam carrier projecting into the ribbon space of the spool, substantially as set forth.

7. The combination in a typewriter machine of a pair of ribbon spools each having a gear pinion attached, movable driving pinions adapted to engage and disengage said spool pinions respectively, a movable cam carrier carried by each of said spools adapted to engage the driving pinion and shift the position of the same, a connection between the driving pinions of each spool spacing the pinions so that only one at a time can be in driving engagement, a tooth on said connection, and a spring click for securing the position of the pinions and assisting their movement, substantially as set forth.

8. The combination in a typewriter machine of a pair of ribbon spools, each having a gear pinion attached, movable driving pinions adapted to engage and be disengaged from said spool pinions respectively, swinging hangers having bearings carrying the shafts of said driving pinions respectively, a connection between the hangers of said

shafts arranged to space the pinions so that only one shall be in driving position at a time, cams mounted on the spools and adapted to throw in said driving pinions respectively, and a spring click assisting the movement of throwing in the driving pinion, substantially as set forth.

9. In a typewriting machine a pair of ribbon spools, a pair of shiftable driving pinions for said spools adapted to alternately engage their respective spools, a movable cam mounted on each of said spools and means placing the cams under the control of the ribbon whereby the same are adapted to be shifted into a plane with and to engage with and shift its driving pinion and to be shifted to avoid such engagement, substantially as set forth.

In witness whereof, I have affixed my signature, in presence of two witnesses, this 11th day of Nov. 1907.
